Patented Feb. 7, 1967

206,882

CHRISTMAS TREE ORNAMENT

Dario Moranduzzo, Via Aretina 161,
Florence, Italy

Filed Oct. 22, 1965, Ser. No. 87,820

Term of patent 14 years

(Cl. D29—1)

FIGURE 1 is a side elevational view of a Christmas tree ornament showing my new design, the other two sides being similarly ornamented;

I claim:

The ornamental design for a Christmas tree ornament, as shown and described.
